X-RAY APPARATUS

Arthur J. Kizaur, Wauwatosa, Wis., assignor to
General Electric Company, a corporation of
New York

Application May 27, 1949, Serial No. 95,752

16 Claims. (Cl. 250—47)

1

The present invention relates in general to X-ray apparatus, and has more particular reference to improved apparatus for the X-ray examination of patients, as by radiography and fluoroscopy, the invention pertaining to table means for supporting patients for examination, in various easily obtained positions, and associated readily operable equipment for X-ray photography and fluoroscopy of patients in such various positions, including facilities for tele-radiographic purposes, where the source of X-rays is disposed at a substantial distance from the subject being examined.

Radiography is the art of making X-ray photography of a subject to be pictured on suitable X-ray sensitive material, while fluoroscopy is the establishment and observation of X-ray shadow pictures, on a suitable X-ray sensitive screen, of a subject under examination. It is desirable, especially in radiography and fluoroscopy of human subjects, to be able to examine the subject in a variety of body positions, including the horizontal, vertical and various intermediate inclined positions. It is also desirable, in many cases urgently so, to examine and picture the subject rapidly in several different body positions, and hence to move the subject to such positions with maximum speed and minimum disturbance, to adjust and operate the radiographic and fluoroscopic equipment speedily in all of such different positions.

An important object of the present invention, therefore, is to provide apparatus of the character mentioned, including readily adjustable means for supporting a subject in any one of a plurality of positions, and operable to shift rapidly from any one to any other position, smoothly and substantially without disturbing the subject, in combination with auxiliary equipment for radiography and fluoroscopy arranged to be rapidly adjusted for operation in all adjustable positions of the subject being pictured.

Another important object is to provide for the X-ray examination and photography of subjects by means of an X-ray source disposed at a substantial distance from the subject; another object being to provide readily adjustable means for mounting the X-ray source either at a substantial distance from, or immediately adjacent, the subject; a still further object being to provide for mounting the source for the projection of X-rays horizontally when in the remotely disposed position, and vertically, in a downward direction, when in position close to the subject.

Another object is to provide improved support means for an X-ray source, whereby the source may be rapidly disposed in position for tele-radiographic or far X-ray purposes, at a substantial distance from a subject, supported for examination, as on a table, and as rapidly returned to position adjacent the patient for rela-

2

tively near X-ray purposes; a further object being to provide a horizontally adjustable support track of novel construction and attached on the support table so that the X-ray source will bear a definite relationship to the table, and hence to a patient supported thereon for examination, and may also be rapidly and easily adjusted on said support for either near or far X-ray purposes.

Another object is to form the horizontally extensible support track as a relatively low structure offering minimum obstruction against access to the table at the side thereof where the track is mounted; a further object being to form the extensible structure as a flat, low platform adapted to be walked upon and on which the operating technician at will may stand close to the table, to facilitate observation of the patient or operation of the apparatus.

Another important object is to provide novel means for securing the parts in adjusted position and for releasing the same for adjustment; a further object being to provide anchoring means for the several adjustable parts of the apparatus and manual control means constructed and arranged to allow for operation thereof at a common conveniently located control station.

Another important object is to provide an improved manual control for a plurality of anchoring devices wherein a single handle may be employed to control the several anchoring devices individually.

Another object is to provide an improved manual control for a plurality of operable devices embodying telescopically arranged drive shafts having adjacently disposed operating handles for selective one-handed operation at a convenient control station.

Another object is to provide mechanism comprising telescopically arranged shaft devices having operating handles for controlling a plurality of separate operable devices from a common conveniently located control station, wherein the control handles may be located at will in any selected one of a plurality of possible handle locations, to suit the convenience of the operator in the various adjusted positions of the apparatus.

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a perspective view of apparatus embodying the present invention;

Fig. 2 is a front view of the same, with covers removed to reveal structural details;

Fig. 3 is an end view of the apparatus shown in Fig. 2, as seen from the left;

Fig. 4 is an enlarged perspective view of a portion of the apparatus;

Figs. 5 and 6 are sectional views, respectively taken substantially along the lines 5—5 and 6—6 in Fig. 4;

Figs. 7 and 8 are sectional views, respectively taken substantially along the lines 7—7 and 8—8 in Fig. 6;

Figs. 9 and 12 are sectional views, respectively taken substantially along the lines 9—9 and 10—12 in Fig. 2;

Figs. 10, 11, and 13 are sectional views, respectively taken substantially along the lines 10—10, 11—11, and 13—13 in Figs. 9, 10, and 12; and

Fig. 14 is a sectional view taken substantially along the line 14—14 in Fig. 12.

To illustrate the invention, the drawings show X-ray apparatus, including a support 21 for a subject to be examined, means to support X-ray sensitive material as well as fluorescent screen means, adjacent the examination subject, and one or more X-ray sources, including an X-ray source 54 suitably supported in position to emit rays and direct the same upon the subject to be examined, means including a transformer 20 and suitable cables for energizing the source 54, and a suitable control panel 19 carrying devices and mechanisms for the operation of the X-ray apparatus.

The support 21 may conveniently comprise a tilting structure forming a table 22 and support means 23 on which the table is carried for tilting movement. As shown, the table may comprise transverse end members 24 and longitudinal side members 25 and 26 of preferably hollow, box-like sheet metal construction, to provide adequate rigidity in a relatively light-weight structure, said members being secured together, as by welding the same, to form a preferably rectangular frame 27. A table top panel 28 may be secured to the frame, as by suitable mounting brackets 29 preferably disposed at the opposite ends of the top panel and frame to provide a clear space or opening 30, behind the panel and between it and its supporting frame 29.

The support means preferably comprises hollow, yet rigid, sheet metal construction in the interests of adequate strength and minimum weight, said structure providing a relatively thin panel-like upright portion 31 at a side of the table, intermediate its ends, and a transverse leg 32 secured on and extending from the upright portion, beneath and transversely of the table. The panel-like upright 31 may be formed with a cut-out portion 33 to provide space for the accommodation of the toes of an operator standing next to the table, said cut-out portion defining a ground engaging foot 34 at one end of the upright. An adjustable foot 35, for leveling purposes in a longitudinal direction, may be provided on the upright 31 at the end of the cut-out portion 33 remote from the foot 34. Transverse leveling of the table may be accomplished, as hereinafter described, by means of adjustable feet similar to the foot 35, and mounted at the end of the transverse leg 32 remote from the upright 31.

The table frame 27 is mounted on the upright for tilting movement in any suitable or preferred fashion. As shown, the mounting of the table frame preferably allows the table to be tilted in one direction from a normal, substantially horizontal position to a vertical position, indicated in dotted lines at 27'. The mounting of the table also preferably provides for tilting the same in the opposite direction, as indicated in dotted

lines at 27"; and means is preferably provided for locking the table in any desired tilted position intermediate the positions shown at 27, 27', and 27".

The table mounting is also preferably arranged so that the table frame is supported on one side only, so that the opposite side may be entirely free and unobstructed, the table frame supporting longitudinally movable carriages 36 and 37 on suitable roller trackways on the frame. These carriages are adjustably shiftable longitudinally of the table frame, and may be secured in any adjusted position between the opposite ends of the frame. The carriage 36 is mounted for movement immediately beneath the table top panel 28, opposite the opening 30, and provides for the reception of X-ray film cassette means which may be loaded into and removed from the carriage 36 through the opening 30. The carriage 36 may also contain a Bucky diaphragm and conventional diaphragm shifting mechanism, so that X-ray pictures may be made on film in a cassette in the carriage 36 by exposing the film to X-rays emanating from a source located above or in front of the panel 28, through an object or patient, to be pictured, disposed upon or in front of the upper surface of the panel 28. Power for the operation and control of the Bucky diaphragm apparatus may, of course, be supplied through the transformer means 20.

The carriage 37, which is longitudinally shiftable on the frame 27, beneath the carriage 36, may likewise be adjustably shifted and secured in any desired position of adjustment between the opposite ends of the table frame. This carriage may provide a mounting for a suitable source of X-rays disposed to direct rays through the panel 28 from the back or underside thereof. The carriage 37, to this end, may support an auxiliary frame 38 on which said X-ray source may be mounted, the frame 38 being shiftable on the carriage 37 in a direction transversely of the table. The frame 38 may extend beneath and outwardly of the free or unsupported side of the table frame and may carry, outwardly of said side, an upright support structure 39. The structure 39 extends in position and is formed to support a carrier frame 40 above the table top panel 28, said frame being movable on the support structure 39 in a direction toward and away from the table top, and being anchorable in any desired adjusted position. The frame 40 is adapted to support auxiliary equipment 41 above or in front of the panel 28 and in any desired spaced relation therewith.

This auxiliary equipment 41, being supported on the frames 38 and 40, may not only be adjusted toward and away from the table panel 28, but also may be adjusted laterally and longitudinally of the table, together with the X-ray source, on the frame 38. The apparatus may be disposed at either end of the table, when not in use, in order to leave unobstructed the remaining area above or in front of the table panel 28. The auxiliary equipment 41 may comprise a fluorescent screen adapted to be disposed above or in front of a patient on the panel 28, so that shadow pictures of the patient may be established on the screen by energizing the X-ray source on the frame 38 behind or below the table top, the cassette carriage 36 during such operation, of course, being disposed outwardly of the path of X-rays emanating from such source. The equipment 41 also may include film cassette means, and operating apparatus powered through the transformer means 20, so that a

subject on the table panel 28 may be radio-graphed utilizing the X-ray source on the frame 38.

By supporting the table frame 27 on one side thereof only, the other side is left free and unobstructed so that the upright 39 may be shifted longitudinally to any desired adjusted position. The apparatus 41 also may be adjusted transversely of the table because the frame 38 is transversely shiftable in the carriage 37.

In order thus to tiltably support the table frame on one side thereof only, while providing adequate table rigidity for the support of patients of normal or excessive weight, the box-like frame structure previously described affords adequate table rigidity in a relatively light-weight structure, said hollow frame structure further allowing for the housing therein of carriage shifting and counterbalancing means.

The table frame 27 is tiltably mounted on the upright 31 by means of a single, preferably tubular, link 43 which may comprise a preferably steel tube fitted, at its opposite ends, with bearings 44 and 45. The bearing 44, at one end of the tube, is pivotally mounted in a suitable journal 46 at the top of the upright 31. The bearing 45 is pivotally mounted in journal means 47 formed in the longitudinal table frame member 26. Adjacent the journal 46 the upright 31 provides a shoulder 48 in position to engage a foot member 49 on the tubular link 43, so that the link may be supported normally on the upright 31 in substantially horizontal position, the table frame being supported on the link at the bearing and journal means 45, 47, and normally resting on a bearing plate on the link above the journal and bearing means 44, 46. The table frame may thus be normally supported in horizontal position.

Table tilting means, preferably in the form of an extensible hydraulic cylinder 50 and cooperating piston 51, may be provided. As shown, the cylinder 50 may be tiltably mounted, as at 52, on the upright 31, and the piston 51 may be pivotally connected, as at 53, at one end of the table frame. By operating the tilting mechanism in one direction, the table frame may be tilted on the pivot means 45 and 47 to the inclined position shown at 27", or to any intermediate position. By operating the tilting mechanism in the opposite direction, the table and link 43 may be tilted in the opposite direction on the bearing means 44, 46, to the vertical position shown at 27', or to any intermediate position.

Manually operable or other suitable tilting means may, of course, be employed in place of the hydraulic means shown. Hydraulically operated tilting means 50, 51, however, is preferred and may be actuated by a suitable fluid medium placed under pressure, as by a motor driven pump, and delivered thence to the cylinder 50 under control of suitable valves, which may conveniently be operated by foot pedals 50' mounted on the pedestal 31, as in the toe space 33. The pump and its driving motor may be mounted on the transverse leg 32 of the table support, and the motor may be powered through the transformer means 20.

The carriage means 36 and 37 are preferably counterbalanced, as by means of weights operatively connected therewith and movable within the hollow members of the frame 27, and hydraulic or other suitable means, which if desired may be disposed within the hollow frame members, may be provided for adjustably shifting the carriages longitudinally on the frame, so that the same may be thus readily shifted and adjusted

on the frame in horizontal or any relatively tilted position. The carriage 40 likewise is preferably counterbalanced on its supporting upright to facilitate adjustment thereof in any tilted table position. The apparatus thus may be employed for fluoroscopy or radiography in any relatively tilted or horizontal table position, utilizing the X-ray source on the frame 38 beneath or behind the table, in combination with the fluoroscopic screen means or film cassette supporting means comprising the auxiliary equipment 41.

Where such equipment 41 comprises combined cassette and fluoroscopic screen means, it will be apparent that considerable facility is afforded, in that the operator of the apparatus may observe a picture of the patient on the fluoroscopic screen and, if wishing to make a permanent picture of the patient, may rapidly adjust the cassette means and picture what has just been observed on the fluorescent screen. Furthermore, since the table may be rapidly and almost instantly tilted in either direction, without disturbing the patient or requiring alteration of patient position on the table, fluoroscopic examination and radiography of the patient is greatly facilitated.

In addition to the foregoing advantages, the cassette carriage 36 also affords facilities for making large size radiographs of a patient on the table, in conjunction with a suitable source of X-rays 54 disposable above or in front of the panel 28; and the present invention particularly contemplates the provision of mechanism 55 whereby such source of X-rays 54 may be disposed above the panel 28 in position to direct rays vertically downwardly upon the table when the same is in horizontal position, or may direct the rays at any desired inclination upon the table, either when the same is horizontal or at any inclination; such mechanism 55 further providing for the disposition of the source 54 at a substantial distance from the table structure, for tele-radiographic purposes, especially when the table is in the vertical position as indicated at 27'.

To this end, an extensible trackway structure 56 is secured to the table support frame, said structure 56, as shown, comprising a preferably hollow, elongated sheet metal box 57 extending along and beneath the unsupported side of the table frame and provided, medially of said box, with an upstanding mounting flange 58, whereby said box may be bolted or otherwise secured to the transverse leg 32 of the table supporting frame structure, as at the end of said leg 32 remote from the upstanding panel portion 31 of said frame. The box member 57 thus forms a rigidly connected part of the table supporting frame; and said box structure, at intervals, may be provided with adjustable foot members 59, similar to the adjustable foot 35, for leveling purposes.

It will be seen from the foregoing that the box member 57 will extend longitudinally in parallelism with respect to the table and in the direction of tilting movement thereof. The box-like member 57, although of preferably hollow, light-weight construction, provides a rigid support for an extension track member 60, which likewise may be formed of elongated sheet metal pieces to provide a rigid, preferably hollow beam having lateral downwardly bent flanges 61 along the opposed longitudinal side edges of the beam. Channel members 62, forming inner facing tracks, and channel members 63, forming out-

wardly facing tracks, may be secured on and along the opposite faces of the downwardly turned flanges 61, said channel members 62 and 63 being preferably integrated with and attached to the beam 60, as by welding.

The box member 57, at intervals therein, is provided with mounting brackets 64 carrying outwardly extending rollers 65 in position to extend within the track forming channel members 62, whereby the beam 60 is freely shiftable on and with respect to the box member 57 in a direction longitudinally thereof. The beam 60 thus may be adjusted in position above the box member, in centrally alined position with respect to the table support frame, with the opposite ends of the beam in substantial alinement with the opposite ends of the box member. The beam 60, however, is preferably slightly longer than the box member 57, so that one end of the beam may project beyond the corresponding end of the box member when the parts are in relatively contracted or centered relationship, such projecting end of the beam being provided with adjustable feet 66. It will be seen that the beam 60 may be extended on the box member 57 in the direction of said overhanging end of the beam, said direction being the direction in which the table is tiltable to the vertical position 21'. When in such extended position, the adjustable feet 66 may be operated to accurately level the beam, and to anchor it on the floor in both extended and contracted position.

The box and beam are preferably of relatively flat, low configuration so that the same will not obstruct free access to the side of the table along which the track structure extends. The top of the box, between the roller brackets 64, and the entire top of the beam may be finished, as with rubber matting or other suitable covering, to constitute the same as non-slip platform surfaces adapted to be stepped upon and on which the operating technician may stand while examining a subject on the table, or in moving about in adjusting and operating the equipment.

A pedestal structure 67 for supporting the X-ray source 54 is mounted on the beam 60, preferably for adjustment longitudinally thereof, so that said pedestal and the ray source thereon, when the beam is in contracted or centered position on the box-like support member 57, may be adjustably disposed in any desired position of adjustment within the length of the table; and by extending the beam 60 and securing it in extended position, the pedestal 67 and ray source thereon may be disposed at any desired distance from the table, within the limit of the extended length of the beam.

Means is preferably provided for mounting the light source for turning movement on the pedestal about a horizontal axis so that rays from the source 54 may be directed in any desired angular relationship. The ray source supporting mechanism also preferably includes means for adjusting the ray source vertically on the pedestal, and may also provide for angular movement of the ray source about a vertical axis, preferably the axis of the pedestal 67 itself. This facility allows the ray source, when not in use, or when the apparatus is being adjusted between extended and contracted position, to be moved or swung out of alinement with the longitudinal zone of the table.

To these ends, the pedestal 67 may comprise an upright, preferably tubular, sheet metal structure 68 having a top plate 69, and mounted at

5 its lower end on a preferably circular mounting plate 70. This mounting plate 70, in turn, may be supported turnably on a carriage member 71, as by means of roller bearing wheels 73 mounted 10 on the carriage in spaced relation and positioned to guidingly and supportingly receive the edges of the circular mounting plate 70. The pedestal 67 is thus supported for turning movement on the carriage 71 preferably about the axis of a vertical sleeve bearing 72, formed on the carriage for a purpose hereinafter more fully described. Suitable means 74 may be provided for latching the structure against, and at will releasing the same for, turning movement.

15 To this end, the carriage 71 may be provided with a circular rib or bead 75, beneath the plate 70 and centered on the turning axis of the pedestal. This rib 75 may be provided with a plurality of upwardly facing sockets 76 spaced circumferentially on the rim in position to receive a latch pin 77. The latch pin may conveniently be mounted in position extending through an opening 78 in the plate 70 and an opening 79 in a frame member mounted on and above the plate. 20 Spring means 80 may be provided to normally urge the pin in a direction to latchingly engage in the latching sockets 76, the pin having a circumferential shoulder 81 in position to be engaged by a latch releasing cam or finger 82. 25 Spring means 80 may be provided to normally urge the pin in a direction to latchingly engage in the latching sockets 76, the pin having a circumferential shoulder 81 in position to be engaged by a latch releasing cam or finger 82. 30 adapted to move the pin 77 against the influence of the spring 80 to retract the pin from the latching socket, and thus release the pedestal structure for turning movement on the carriage 71.

35 The carriage 71, at its opposite side edges, may be formed with dependent flanges 83 and 84 adapted to overlie the outwardly facing track forming channels 63 on the beam 60, the flanges 83 and 84 being provided with mounting rollers 85 in position to engage in the said track members 63. The flange 84, beneath the rollers 85, 40 may be provided with additional rollers 86, and the box-like member 57, opposite said rollers 86, may likewise be provided with similar rollers 86' at intervals along the side thereof and preferably beneath the rollers 65. These rollers 86 and 45 86' are preferably grooved to receive the spaced flanges of a channel member 87, which is secured along and integrated with the beam 60 beneath the track forming members 62 and 63 on one side 50 of the beam, as clearly shown in Fig. 5 of the drawings. The purpose of the track forming channel 87 and the rollers 86 and 86' is to anchor the beam against transverse movement with respect to the box member 57 and to anchor the carriage 71 against transverse movement with respect to the beam.

55 It will be seen from the foregoing that the carriage and the pedestal 67 are freely movable along the beam 60 by virtue of the rollers 85 and 60 cooperating track channels 63. In order to anchor the carriage in any desired adjusted position on the beam 60, a friction member, comprising a plate 88, is provided on the carriage 71 in order to frictionally engage the upper surface of 65 the beam 60 beneath that portion of the carriage 71 which overlies it. The friction plate 88 is carried on a stem 89 axially movable in the bearing 72, spring means 90 being provided for normally urging the stem on the carriage 71 in a direction to press the friction plate 88 upon the beam 60. The pin 89 extends upwardly of the plate 70 and is connected with a releasing arm or lever 91, pivoted as at 92 on a bracket 93, which, in turn, is mounted on the plate 70. The arm 91 and bracket 93 may conveniently be disposed within

the structure of the pedestal 67, as within the hollow member 68.

In order to actuate the release lever 91 and also the latch pin 77, common means is provided which, when turned in one direction from a neutral position, serves to retract the pin 77 from a locking socket 76 against the influence of the spring 80, and when operated in the reverse direction from neutral position, serves to retract the stem 89 in order to release the friction pad 90 from the beam against the influence of the spring 90. To this end, the releasing means may comprise a shaft 94 journalled in suitable bearings on the plate 70. This shaft may carry a releasing cam 95 in position extending beneath a roller 96 on the release lever 91 at the end thereof remote from the pivot 92, said cam 95 preferably providing a radial shoulder forming the finger 82. When turned in a clockwise direction, viewing Fig. 6 of the drawings, the finger 82 may engage beneath the shoulder 81 on the pin 77 and retract the same to release the plate 70 for turning movement on the frame 71 about the axis of the bearing 72. When turned in a counter-clockwise direction, viewing Fig. 6, the cam 95 may serve to lift the lever 91, thereby raising the stem 89 and releasing the friction pad 88. Manually operable means, hereinafter more fully described, may be provided in convenient position, as on the pedestal 67, for operating the shaft 94 in either direction from a neutral position in the performance of its latch releasing functions.

As shown, the pedestal 67 may conveniently comprise a box-like sheet metal structure 68 formed to provide inwardly facing track forming channels 97, extending vertically along the opposite sides of the member, at the front thereof, a vertical toothed rack 98 being secured, as by means of an anchor bracket 99, at one side of the pedestal, as behind one of the track forming channels 97. The pedestal supports a vertically movable carriage structure 100, preferably comprising a channel member 101 and fitted with roller means 102, at the opposite sides thereof, in position to engage in the vertical tracks 97. This carriage supports the X-ray source 54 on a mounting frame 103 on the carriage. The weight of the carriage and of the ray source and its mounting frame is preferably counterbalanced on the pedestal 67, as by means of a counterweight 104 disposed within the hollow upright 68, said counterweight being hung on one end of a preferably steel wire cord 105, which extends through an opening in the top plate 69 of the pedestal and thence around a pulley 106 journalled in suitable bearings on the top plate, the opposite end of said cord extending from the pulley 106 downwardly and medially between the trackways 97 and being secured to the carriage 100 preferably at or adjacent the upper end thereof.

The roller means 102 may comprise wheels journalled on shafts 107 supported in openings formed in the spaced side walls of the channel member 101, and the structure may be provided with a safety lock to anchor the carriage on the pedestal in the event of breakage of the cord 105. To this end, the shaft 107 may carry a block 108 tiltably mounted thereon between the spaced flanges of the member 101. This block 108 may provide an anchorage for the carriage connected end of the cord 105. The block 108 is mounted in an opening 110 formed in the back of the member 101 in position to face the front surface of the box member 68 immediately behind the

carriage member 101. The block 108 has a clamping cam surface 109 such that when the counterweight is attached on the block 108, the clamping surface of the block may not lockingly engage the forward face of the box member 68. In the event that the cord 105 should break, or the counterweight 104 otherwise become disconnected from the carriage 100, a relatively powerful tension spring 111, connected between the block 109 and a remote anchorage on the member 101, will rotate the block in a direction to wedgingly jam the cam surface 109 against the upright and thereby secure the carriage 100 against unrestricted downward movement on the pedestal.

The carriage 100 is preferably reinforced and rigidified, as by means of an inner channel member 112, secured at its upper end, preferably rockingly, between the spaced flanges of the channel member 101. To this end, a pintle member 113, forming a bushing 114 at one end, is mounted between and integrated with the spaced flanges of the channel member 112, as by welding. Within the said bushing portion 114, and extending outwardly thereof on each side of the member 112, is mounted a stem 115 adapted for pivotal mounting in suitable bearing openings formed in the opposite flanges of the member 101, said pin 115 being preferably integrated with the flanges of the member 112, as by welding. The lower end of the member 112 also is supported adjustably on the frame member 101, preferably as by means of a threaded stud 116 fastened on the member 101 and adjustable clamping nuts 117, by means of which the member 112 may be secured on the frame and angularly adjusted about the axis of the stem 115 by means of the nuts 117. The pintle member 113 thus may be supported on the carriage 100 with its axis accurately adjusted in horizontal position.

The frame 103 is mounted on the pintle 113 so that the X-ray source 54 may be supported in position outwardly of the pedestal 67 within the zone of the tilting table 27. The frame 103 also is angularly movable on the pintle 113 so that the angular direction of the X-ray beam from the source 54 may be accurately adjusted.

To this end, the frame 103 may comprise a pair of spaced apart members 118 interconnected in spaced relationship at one end by means of a preferably hollow, box-like structure 119, providing a central bearing 120 adapted for turnable movement on the pintle 113, the opposite ends of the members 118 being rigidly interconnected by a cross member 121. Adjacent the bearing 120 the pintle 113 has a preferably circular plate or disk 122 fixed thereon and extending outwardly of the pintle within the box-like structure 119. Within the box-like structure 119 is mounted, as on a pivot pin 123, a brake member 124 adapted to frictionally engage a surface of the plate 122. This brake member 124 may be operated by means of a threaded stem 125 connected with the plate and extending thence to and outwardly of the cross member 121 of the frame 103, the outwardly projecting end of the stem 125 being provided with an operating handle 126. By operating the handle 126, the brake 124 may be released to permit the frame 103 to be rotated on the spindle 113, or to secure the frame 103 in any desired relative angular position on the spindle.

On the frame 103, and adjustable thereon longitudinally of the members 118, is a mounting

11

frame 127 slidable in suitable trackways formed in the members 118. Suitable means controlled as by an operating handle 126' may be provided to adjust and secure the mounting frame 127 in any selected position lengthwise of the members 118. This mounting frame 127 is preferably formed with a circular seat 128 in which a carrying frame 129 is turnably mounted. This carrying frame 129 supports a preferably shock-proof casing 130 of any suitable or conventional form, within which an X-ray tube forming the ray source 54 is mounted. Clamp means, preferably controlled by a manually operable handle 131, may be provided on the frame 127 to secure the carrying frame 129 and the X-ray source thereon in any position of relative angular adjustment on the frame 127.

It will be seen from the foregoing that the light source may be supported on the pedestal 67 at any desired elevation thereon; may be mounted at any desired position spaced from the pedestal on the frame 103; may be disposed at any desired angular inclination in a plane at right angles with respect to the frame 103, by tiltingly adjusting the same on the spindle 113; may be adjusted to any desired angularity in a plane longitudinally of the frame 103 by adjustment of the carrying frame 129 on the mounting frame 127; may be swung about the vertical axis of the pedestal; and may be moved to any desired position longitudinally of the tilting table by adjustment of the carriage 71 on the beam 60 and by adjustment of the beam 60 on the box-like portion 57 of the table support structure, suitable latching mechanism being provided for securing the several parts in selected positions of adjustment.

In order to releasably secure the vertically shiftable carriage 100 in adjusted position on the pedestal 67, and to operate the latch releasing shaft 94, all from a conveniently located control, a housing, comprising a sleeve-like member 132 having an enlarged base 133, is fastened, as by means of the bolts 134, on the carriage member 101 in position extending outwardly of a side thereof. This housing contains a sleeve member 135 turnably mounted therein and having an end 136 extending outwardly of the end of the sleeve 132 remote from its carriage mounted end. The inner end of the sleeve 135 carries a disk 137 secured thereon and extending outwardly of the inner end of the sleeve, whereby the sleeve 135 may be held in the sleeve 132 by means of a holding ring 138 which encircles the sleeve 135 behind the disk 137, the ring 138 being held in the sleeve by suitable set screws 139. To facilitate assembly of the sleeve 135 into the sleeve 132, a helical spring 140 may be assembled around the sleeve 135 in position engaging between a shoulder 141 on the sleeve and the ring 138 to maintain the ring, during assembly, in position snugly against the disk 137 to receive the fastening screws 139.

The inner end of the sleeve 132 is preferably welded, as at 142, on a latch block 143 which, as by welding, is integrated with and forms a part of the mounting base 133. The disk 137, in its surface facing the mounting block, is formed with a plurality of latching cavities 144 in position to receive spring pressed latch pins 145, contained in cavities formed in the block 143, the cavities and pins being preferably equally spaced apart circularly in the disk 137 and in the block 143. As a consequence, the sleeve 135 will be normally latched against relative turning movement within the sleeve 132 and with respect

the connected shaft 159 in one direction or the other, the shaft 161 may likewise be turned in one direction or the other in order to correspondingly turn the shaft 94 and thus release the latching pin 77 and friction plate 88, the square form of the shaft 161 and its splined relationship with the gear 151 allowing free vertical movement of the carriage 100 and apparatus mounted thereon without affecting the shaft or the latched condition of the pin 77 and friction plate 88.

In order to provide for operation of the gears 148 and 160 from a convenient location, the outer end 136 of the sleeve 135 is fitted with a radially extending, preferably tapered, sleeve-like handle 165, secured on the sleeve 135 in position opening into the chamber 149. This handle, at its inner end within the chamber 149, journals a bevel gear 166 in position making driving engagement with the gear 148. This gear 166 is 10 drivingly connected with a tube 167, which extends through the sleeve-like handle 165 and projects at the outer end thereof where said sleeve 167 is fitted with a manually operable handle or wheel 168, by means of which the tube 25 and connected gear 166 may be turned. Within the gear 166 and sleeve 167 is journaled a shaft 169 fitted with a bevel gear 170 extending in the chamber 149, in position to drivingly engage with the gear 160, the shaft 169 extending through the tube 167 and projecting at the outer end thereof, said projecting end of the shaft 169 being fitted with a manually operable handle 171 adjacent the handle 168 and outwardly thereof.

These handles 168 and 171 are preferably circular, the handle 168 being of somewhat larger diameter than the handle 171 to facilitate manipulation thereof. These handles are preferably disposed adjacent and beneath the outer end of the frame 103 for convenient manipulation, although, since the sleeve 135 on which the arm 165 is mounted is freely turnable in the mounting sleeve 132, said handle 168 may be turned to any desired angular position about the axis of the sleeve 135 and latched in such angular position by operation of the latching pins 145. This adjustment of the arm 165 may be accomplished without moving either of the gears 148 and 160, since the gears 166 and 170 and the connected handles 168 and 171 may turn freely in the sleeve 165 during such angular adjustment thereof without causing the gears 148 and 160 to turn. Accordingly, adjustment of the projecting handle 165 to any desired convenient position circularly about the axis of the sleeve 132 may be accomplished without interfering with the locked or unlocked condition of the gear 154, and without interference with the latching pin 77 and the friction plate 88. In order to counterbalance the weight of the arm 165 in horizontal position, the spring 140 may be used, in torsion, by providing outstanding fingers 140' at the opposite ends of the spring and fitting into sockets formed in the sleeve 135 and in the ring 138, which is secured to the housing assembly 132, 33, 143, on the carriage. When the carriage 103 is on the pedestal at or below the eye level of the operator, the arm 165 may be adjusted in position parallel to the frame 103 to present the operating handles 168 and 171 in position adjacent the outer end of the frame near the handle means 126, 126', whereby all of the control handles, including the handle 131, are in convenient adjacent position to 75

control all of the adjustments of the X-ray source supporting structure. When the frame 103 is at an elevation on the pedestal in which the handles 168 and 171 are out of convenient reach, if the arm 165 is in horizontal position, the arm 168 may be rotated downwardly to any desired position, including the vertical, to present the handles 168 and 171 at a convenient elevation for manipulation.

The outer open end of the cavity 149, of course, may be closed by means of a suitable cover.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention; no claim being herein made to the structure of the tilting table, per se, nor the combination therewith of the frames 37, 38, and 39, nor to the apparatus mounted on said frames, since the same form the subject matter of co-pending applications for United States Letters Patent, as follows: Applications Serial Nos. 4,446, now Patent No. 2,568,236, and 85,850, filed respectively on January 26, 1948, and April 6, 1949, on inventions of Arthur J. Kizaur in Table Construction, and an application Serial No. 104,903, filed July 15, 1949, on an invention of Arthur J. Kizaur relating to X-ray protective screen means, now Patent No. 2,567,566.

The invention is hereby claimed as follows:

1. X-ray apparatus comprising a support frame, a table including a top panel mounted on said frame, means for supporting sheet material sensitive to X-rays on said table behind said panel, a track, on said frame and extending at one side of said table, said track forming a footing for said frame, an upright support pedestal on said track and adjustable longitudinally thereof, a carriage vertically adjustable on said pedestal, means for mounting an X-ray source on said carriage in position to direct rays toward said table, counterbalance means for counterbalancing said carriage on said pedestal, and normally inoperative safety clamp means operable to hold said carriage against movement on said pedestal in the event of disconnection therefrom of said counterbalancing means.

2. X-ray apparatus comprising a support frame and a top panel forming a table, means for supporting sheet material sensitive to X-rays on said table behind said panel, means forming a pedestal mount on said frame at one side of said table, an upright support pedestal on said mount and extending upwardly of said table, a carriage vertically adjustable on said pedestal, means for mounting an X-ray source on said carriage in position to direct rays toward said table, counterbalance means for counterbalancing said carriage on said pedestal, and safety means for locking said carriage against movement on said pedestal in the event of disconnection therefrom of said counterbalancing means, comprising a brake element rockable on a pivot axis on said carriage in position to brakingly engage said pedestal, bias means normally urging said braking element in a direction on its pivot axis, toward engagement with said pedestal, and means to connect the counterbalance means on said brake element to hold it out of engagement with the pedestal against the influence of said bias means.

3. X-ray apparatus comprising a support frame, a table including a top panel on said frame, means for supporting sheet material sensitive to X-rays on said table behind said panel, a track, on said frame and extending at one side of said table, said track forming a footing for said frame, an upright support pedestal on said track and adjustable longitudinally thereof, a carriage vertically adjustable on said pedestal, cooperating roller and track means on said carriage and pedestal for maintaining the carriage against transverse movement with respect to the pedestal, a support frame carrying a projecting spindle on said carriage, said support frame being adjustably tiltable on the carriage to adjust the angularity of the spindle with respect to the pedestal, a mounting frame for an X-ray source turnably supported on said spindle, and means to secure said mounting frame in angularly adjusted position on said spindle.

4. X-ray apparatus comprising a support frame and a top panel forming a table, means for supporting sheet material sensitive to X-rays on said table behind said panel, means forming a track, on said frame, at one side of said table, a pedestal carriage riding upon and adjustable on the frame longitudinally of the table, an upright support pedestal on said pedestal carriage and adjustably turnable thereon about a vertical axis, means to mount an X-ray source on said pedestal, anchor means for securing the pedestal carriage in adjusted position on the track, latch means for securing the pedestal in adjustably turned position on the carriage, said anchor and latch means each comprising a shiftable fastening member normally urged to fastening position, and manually operable means comprising an actuating cam turnable in opposite directions from neutral position for the respective retraction of said members from fastening position.

5. X-ray apparatus comprising a support frame and a top panel forming a table, means for supporting sheet material sensitive to X-rays on said table behind said panel, means forming a track, on said frame, at one side of said table, a pedestal carriage riding upon and adjustable on the frame longitudinally of the table, an upright support pedestal on said pedestal carriage and adjustably turnable thereon about a vertical axis, means to mount an X-ray source on said pedestal, anchor means for securing the pedestal carriage in adjusted position on the track, latch means for securing the pedestal in adjustably turned position on the carriage, said X-ray source being mounted on a source carriage vertically shiftable on said pedestal, and manually operable means comprising an operating shaft turnably mounted on said source carriage and movable therewith and having an operating handle, and driving means including a spline shaft drivingly connected with said operating shaft and with said latch and anchor means to actuate the same in response to manual operation of said handle regardless of the vertical position of the source carriage on the pedestal.

6. X-ray apparatus comprising a support frame and a top panel forming a table, means for supporting sheet material sensitive to X-rays on said table behind said panel, means forming a track, on said frame, at one side of said table, a pedestal carriage riding upon and adjustable on the frame longitudinally of the table, an upright support pedestal on said pedestal carriage and adjustably turnable thereon about a vertical axis, means to mount an X-ray source on said pedestal, anchor

means for securing the pedestal carriage in adjusted position on the track, latch means for securing the pedestal in adjustably turned position on the carriage, said X-ray source being mounted on a source carriage vertically shiftable on said pedestal, means to anchor said source carriage in vertically adjusted position on the pedestal, comprising a hollow shaft turnably mounted on the source carriage and adjustable in one direction to anchor and in the other direction to release the source carriage on the pedestal, said hollow shaft having a manually operable handle at one end, manually operable means comprising an operating shaft turnably mounted on said source carriage within said hollow shaft and having operating handle means at and outwardly of the handle carrying end of said hollow shaft, whereby said handle and handle means are disposed in adjacent relationship for convenient selective one-handed operation, and driving means including a spline shaft drivingly connected with said operating shaft and with said latch and anchor means to actuate the same in response to manual operation of said handle means regardless of the vertical position of the source carriage on the pedestal.

7. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, a carriage mounted on said beam for movement longitudinally thereof, and means to mount an X-ray source on said carriage in position to direct rays toward said table.

8. X-ray apparatus comprising a support frame and a top panel forming a table, means for supporting sheet material sensitive to X-rays on said table behind said panel, an extensible track structure, on said frame, at one side of said table and comprising an elongated frame member secured on and forming a footing for said support frame, bearing rollers in spaced apart position on said frame member, an elongated beam supported on said rollers for movement longitudinally of said frame member, said beam forming a trackway longitudinally thereof, a pedestal carriage mounted on said trackway for movement longitudinally of said beam, an upright support pedestal on said pedestal carriage, and means to mount an X-ray source on said pedestal in position to direct rays toward said table.

9. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, a carriage mounted on said beam for movement longitudinally thereof, means for maintaining said carriage at all times against movement transversely of said track structure, comprising track means on said beam extending throughout the length thereof, rollers on said frame member holding said track means against movement laterally of the frame member, and rollers on said carriage holding it against lateral movement on the track means, and means to

mount an X-ray source on said carriage in position to direct rays toward said table.

10. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, adjustable support means on the beam at an end thereof for leveling and anchoring the same when in extended position, a carriage mounted on said beam for movement longitudinally thereof, and means to mount an X-ray source on said carriage in position to direct rays toward said table.

11. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, a carriage mounted on said beam for movement longitudinally thereof, means to mount an X-ray source on said carriage in position to direct rays toward said table, and manually releasable anchor means on said carriage for securing the same in longitudinally adjusted position on said beam.

12. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, a carriage mounted on said beam for movement longitudinally thereof, an upright support pedestal turnably supported on said carriage, manually releasable latch means on said upright support pedestal for latching the same against turning movement on said carriage, and means to mount an X-ray source on said pedestal in position to direct rays toward said table.

13. X-ray apparatus comprising a support frame and a top panel forming a table, means for supporting sheet material sensitive to X-rays on said table behind said panel, an extensible track structure on said frame, at one side of said table and comprising an elongated frame member secured on and forming a footing for said support frame, an elongated beam supported on said frame member and adjustable longitudinally thereof, a carriage mounted on said beam for movement longitudinally thereof, an upright support pedestal turnably supported on said carriage, latch means for anchoring the pedestal against turning movement on the carriage, anchor means for securing the carriage against longitudinal movement on said beam, and manually operable means on said pedestal and adapted for actuation in one direction from a neutral position to release said latch means, and in the other direction to release said anchor means.

14. X-ray apparatus comprising a support frame and a top panel forming a table, means for supporting sheet material sensitive to X-rays on said table behind said panel, means forming a

pedestal mount, on said frame, at one side of said table, an upright support pedestal turnably supported on said mount, anchor means for securing said pedestal in adjustably turned position on said mount, a support carriage vertically adjustable on said pedestal, fastening means operable to secure said support carriage in adjusted position on said pedestal, a pair of operating shafts, one turnable within the other and both turnably supported on said support carriage, said shafts being operatively connected respectively to actuate said anchor and said fastening means, manually operable means for turning said shafts, and means to mount an X-ray source on said pedestal.

15. X-ray apparatus as set forth in claim 14 wherein the inner of said operating shafts has a projecting end extending outwardly of an end of the outer operating shaft, a bevel gear on said projecting end, a collar forming a bevel gear on the outer operating shaft behind and adjacent the gear on the inner operating shaft, an enclosing sleeve turnably mounted on the support carriage for rotation about the longitudinal axis of the sleeve in position enclosing said operating shafts and said gears, an arm on and extending radially of said sleeve opposite said gears, a pair of driving shafts, one turnable within the other and both turnably supported on said arm, said driving shafts having bevel geared connection respectively with said bevel gears on the operating shafts, at the sleeve connected end of said arm, and having each a manually operable handle at the sleeve remote end of the arm, said handles being adjacently disposed, the one behind the other for convenient selective one-handed operation, and means to latch the sleeve and arm in selectively adjustable angular position with respect to the support frame.

16. X-ray apparatus comprising a support frame and a top panel forming a table, means for supporting sheet material sensitive to X-rays on said table behind said panel, means forming a pedestal mount, on said frame, at one side of said table, an upright support pedestal on said mount, a carriage vertically adjustable on said pedestal, an adjustable carrying yoke mounted on the carriage for adjustable tilting movement about a horizontal tilting axis, and a mounting frame supported on said yoke for turning movement, on a horizontal axis lying in a plane normal to said yoke tilting axis, in position extending outwardly of said pedestal, said mounting frame providing a support for a source of X-rays, whereby said source may be disposed in adjusted position vertically of said table and angularly on said horizontal axis.

ARTHUR J. KIZAUR.
